(57) **CLAIM**

We claim the ornamental design for a television with rollable display, as shown and described.

DESCRIPTION

FIG. 1 is a top and rear perspective view of a television with rollable display, shown with the display in a rolled in configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top and front perspective view thereof, shown in condition of use with the display in an extended configuration;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.

The broken lines depict portions of the television with rollable display in which the design is embodied that form no part of the claimed design.

1 Claim, 14 Drawing Sheets
